Inventor:

Charles S. Bonney.

United States Patent Office.

CHARLES S. BONNEY, OF PENN YAN, NEW YORK.

Letters Patent No. 76,984, dated April 21, 1868.

IMPROVEMENT IN THILL-COUPING.

The Schedule referred to in these Letters Patent and making part of the same.

TO ALL WHOM IT MAY CONCERN:

Be it known that I, CHARLES S. BONNEY, of Penn Yan, in the county of Yates, and State of New York, have invented a new and useful Improvement in Thill-Coupling; and I do hereby declare that the following is a full, clear, and exact description of the construction and operation of the same, reference being had to the annexed drawing, making a part of this specification, in which—

Figure 1 is a side view, with a portion removed to show the internal construction of the same.

Figure 2 is a side view, with the forward end of the thill at the ground.

The letters of reference refer to the same parts in each figure.

The nature of my invention consists in making a thill-coupling that may be readily united and securely fastened, and may be prevented from rattling by raising the thills and turning up a screw-bolt as the parts wear away.

To enable others skilled in the art to make and use my invention, I will describe its mode of construction and operation.

A is the rear part, that is fastened to the axle in any ordinary manner. The forward portion is made with a chamber that contains the bolt F, leather or rubber, G, sliding journal-box, D, and it is provided with a set-screw that holds the journal-box snugly against the leather, G, as represented in fig. 1.

B is the upper and forward part, that is attached to the thills. Its exterior shape is represented in fig. 2, and its interior is represented in fig. 1, where a part is removed to show it and the other parts. It is made to fit the outside and upper portion of the part A, and it has a pin or bolt, that holds it to the part A, and a channel in the forward part, that passes down over the head of the screw E when the thill is lowered to the ground, or position where it is used.

C is a piece of the thill, bolted to the part B in the ordinary manner.

D is a sliding journal-box; it is fitted within the chamber of the part A, as shown in fig. 1.

E is a screw-bolt; it is provided with a cubical head that will allow the channel, H, to pass over it. Its use is to push the journal-box against the leather, G, and thus clasp the pin, F, and hold the parts, A and B, together; and by turning this screw, when the leather G or pin F is worn, rattling can at any time be prevented. To turn this screw, raise the thill nearly vertical, as shown in fig. 1, and the head of the screw-bolt will be exposed, so that a wrench or screw-driver may be readily applied to it.

F is a pin or bolt, that extends through the part B, and it must be securely fastened by riveting the ends or otherwise. This forms the pivot, upon which the parts are turned as a hinge. To put the two parts A and B together, turn the screw E back, so that the journal-box, D, may be moved forward far enough to allow the leather, G, to open and receive the pin, then, by turning the screw in again, the pin will be securely held in its place.

G is a piece of leather or rubber, fitted within the part A, so as to nearly surround the pin F, as shown in fig. 1.

H is a channel, made in the forward and lower part of B, as shown in fig. 1. It must be made large enough to pass freely over the head of the bolt or screw E, and its use is to prevent the screw, E, from being turned by the action of the carriage to which it is applied.

Having thus fully described my invention, what I claim as new, and desire to secure by Letters Patent, is—

1. I claim the construction and arrangement of the parts A D and screw E, when made and used as and for the purpose set forth.

2. I claim the part B, with the channel H, to prevent the screw E from turning, when made and applied to the part A, substantially as herein specified.

CHARLES S. BONNEY.
